his Atty.

UNITED STATES PATENT OFFICE

2,023,202

MOP

Charles E. Krebs, Chicago, Ill.

Application October 22, 1934, Serial No. 749,375

3 Claims. (Cl. 15—147)

This invention relates to mops and one of its objects is to provide a mop swab having a pocket therein for containing an insertable and removable frame which is provided with a handle swiveled thereto. Another object is to provide a mop swab with a frame holding pocket in its upper side, and having a slit or opening at one end, through which the frame may be inserted into the pocket. Another object is to provide a pocket having a small hole in its upper wall through which the handle is inserted when attaching the mop swab to the frame. This arrangement makes it possible to provide a hole in the upper wall of the pocket of no greater size than the diameter of the handle. Another object is to provide a flap at the end of the pocket, containing the slit or opening, which overlies an end of the frame and acts to confine the frame in the pocket besides protecting the fastening device which is employed to hold the slit closed. Another object is to provide a mop that may be given various shapes, as for instance, round, triangular or rectangular. The round shape has an added advantage in that the mop swab may be adjusted around the frame to distribute the wear on the mop swab. Another object is to provide a simple, strong and rigid frame, having the mop handle permanently connected thereto, thereby providing a unitary structure free from springs and other objectionable connections.

With these and other objects and advantages in view, this invention consists in the several novel features hereinafter fully set forth and claimed.

35 The invention is clearly illustrated in the drawing accompanying this specification, in which:

Fig. 1 is a perspective view of a mop embodying a simple form of the present invention, showing the handle partly broken away;

40 Fig. 2 is a perspective view of the mop swab detached from the frame and handle;

Fig. 3 is a side elevation of the frame and a fragment of the handle;

45 Fig. 4 is a plan thereof;

Fig. 5 is a central vertical section through the mop;

Fig. 6 is a view similar to Fig. 5, but showing the frame and handle in a position occupied when inserting the same into the pocket, and

50 Fig. 7 is a detail vertical fragmental cross section taken at the end of the pocket containing the slit or opening.

Referring to said drawing, which is merely illustrative of one exemplification of the invention, the reference character 10 designates a mop swab

of the kind commonly known as a dust mop or floor mop. At the upper side of the mop swab is a pocket 11 which is formed by upper and lower similarly shaped walls 12, 13, stitched together part way along their marginal edges as at 14, and left unattached at one end to provide an opening or slit through which the hereinafter described frame 15 may be inserted into the pocket. In the upper wall 12 is a hole 16 of relatively small dimensions, through which the handle is inserted 10 when assembling the swab with the frame. The body portion 17 of the mop swab is composed of strands of mop material secured to the underside of the lower wall 13 in any approved manner, as is well understood.

Extending across the opening or slotted end of the pocket is a narrow flap 18, the edge 19 of which is stitched or otherwise fastened to the corresponding edge of the lower wall 13 as at 19, so as to leave only one edge 20 thereof entirely free. The arrangement is such that the flap cannot be withdrawn from the pocket. It is to be observed that the frame 15 extends underneath the flap 18 and is held at that place between the lower wall 13 and the flap. The upper wall 12 overlies the flap 18 and is connected therewith by fastening means 21 here shown in the form of the ordinary and well known snap fastener. Desirably the marginal edge of the upper wall has a strip of binding material 22 stitched thereto, and binding material 23 is provided along the marginal edge of the flap and also along the edges of the lower wall 13, at the gaps between the flap and the places where the upper wall is stitched to the lower one as shown at 24. The binding material covers and protects the raw edges and adds materially to the appearance of the swab.

The frame 15 desirably is formed of wire shaped to fit the pocket. In the form of the invention illustrated, a round mop is shown and the pocket is made round. Consequently in this form, the frame 15 is round. Obviously any other desirable shape may be given to the pocket and frame without departing from the invention. Extending diametrically across the ring or circular part 25 of the frame is a cross wire 26 which is spotwelded thereto at its ends, and the ends of the ring are spotwelded together to 50 provide a strong rigid frame. Desirably the middle portion of the cross wire is offset upwardly as at 27, and swiveled upon this offset portion is a handle socket 28 in which is held a mop handle 29 of suitable length. The mop 55

handle and socket are secured together by a pin or rivet 30.

Conveniently the handle socket is formed from a strip of metal bent transversely upon itself midway between its ends to form an eye 31 that encircles the offset part of the cross wire and the two projecting ends are formed into two companion semi-cylindrical halves which are then brought together to provide the socket for the handle. The bends at the ends of the offset portion 27 of the cross wire position the handle socket upon the frame. It is to be observed that the frame, together with the handle socket and handle, provide a unitary structure which is complete in itself after having been once assembled.

In attaching the mop swab to this unit, the snap fastener members are disconnected from each other, and the handle inserted through the open end of the pocket and pushed out through the hole in the upper wall thereof as seen in Fig. 6, and the frame slid into the pocket. The free edge of the flap is then raised and brought over the adjacent end of the frame, thereby effectively confining it in the pocket. The free part of the upper wall is then brought down upon the flap and fastened thereto with the snap fasteners, thereby completely enclosing the frame in the pocket with the handle socket and handle protruding from the hole in the upper wall. It is not necessary for the frame to fit snugly in the pocket and a little play therein has been found desirable, particularly to facilitate the insertion of the frame into the pocket and under the flap.

The frame provides a rigid and substantial head or backing for the mop swab and the swivel connection with the handle socket permits the handle to adjust itself in the ordinary use of the mop.

With the use of a round pocket and a round frame, the latter may be turned therein, at will, to change the position of the mop swab relative to the frame and thereby distribute the wear to different sections of the swab.

I claim as new and desire to secure by Letters Patent:

1. A mop comprising in combination a mop swab having a pocket in its upper side formed between upper and lower walls and having an opening at one end and a hole in the upper wall, a flap extending into said pocket and secured to an edge thereof with only one edge of the flap left free, and a frame, with a handle swiveled thereto, insertable into said pocket through said opening with one end underlying the flap and with the handle protruding from the hole in the upper wall and co-acting fastening means for securing the upper wall and flap together. 5

2. A mop comprising in combination a mop swab having a pocket in its upper side formed between upper and lower walls, stitched together part way along their marginal edges so as to leave an opening at one end, and there being a hole in the upper wall, a flap extending from the marginal edge of the opening, into the interior of the pocket, said flap having only one free edge, a unitary structure comprising a frame, a handle socket swiveled thereto approximately at the middle thereof, and a handle secured in said socket, said unitary structure being insertable through said opening, into the pocket with one end of the frame inserted underneath the flap, and with the handle protruding from the hole in the upper wall, and co-acting fastening members on the upper wall 30 and flap for securing said wall and flap together at the opening. 20

3. A mop comprising in combination a mop swab having a pocket in its upper side formed between similar upper and lower walls secured together part way along their edges so as to leave an opening at the marginal edge of the pocket, and there being a hole in the upper wall, a frame retaining flap extending into said pocket of said opening, a frame insertable through 40 said opening into the pocket, a handle socket, swiveled upon said frame and protruding from said hole in its upper wall, a handle secured in said socket, and co-acting fastening members for closing said opening. 45

CHARLES E. KREBS.
